United States Patent Office

Des. 224,119
Patented July 4, 1972

224,119

HOCKEY SOUVENIR

William M. Scire, 10 S. Bedford St.,
Woburn, Mass. 01801

Filed Aug. 5, 1970, Ser. No. 24,320

Term of patent 14 years

Int. Cl. D11—02

U.S. Cl. D29—28

Fig. 1.

Fig. 2.

FIG. 1 is a top plan view of a hockey souvenir showing my new design;

FIG. 2 is a front view thereof;

FIG. 3 is a rear elevational view; and

FIG. 4 is a side elevational view, the side opposite being a mirror image thereof.

I claim:

The ornamental design for a hockey souvenir, substantially as shown and described.
